CLAIM

The ornamental design for a toilet brush, as shown and described.

DESCRIPTION

1. Toilet brush
- 1.1 : Perspective
- 1.2 : Perspective
- 1.3 : Top
- 1.4 : Right
- 1.5 : Front
- 1.6 : Back
- 1.7 : Bottom
- 1.8 : Left

A toilet brush comprising a handle and a head; the head comprises an upper surface which connects the handle with a longitudinal axis, a lower surface opposite to the handle, and a lower rim which defines a plane; the longitudinal axis forms an acute angle with the plane of the cleaning head; the lower surface comprises a cavity surrounded by a flange, on which flange the lower rim is defined; in design no. 1, transverse protrusions are formed in the cavity.
